UNITED STATES PATENT OFFICE.

HERBERT LEE HEATH, OF MANILA, PHILIPPINE ISLANDS.

DECORTICATING-BLADE.

1,084,273.

Specification of Letters Patent. Patented Jan. 13, 1914.

Application filed March 25, 1911. Serial No. 616,836.

To all whom it may concern:

Be it known that I, HERBERT LEE HEATH, citizen of the United States, residing at Manila, Philippine Islands, have invented 5 new and useful Improvements in Decorticating-Blades, of which the following is a specification.

My invention relates to an improvement in a device for the treatment of hemp and like 10 materials, in which it is desired to extract the valuable fiber from the stalks and outer casing in which it is contained.

It consists in the employment of a blade having a beveled edge and having the opposite side cut into a series of grooves which 15 intersect the beveled edge.

My invention consists in the parts and the combination and construction of parts as hereinafter more fully described and claimed, 20 having reference to the accompanying drawings, in which—

Figure 1 is a perspective view partly broken away. Fig. 2 is a section on line X—X Fig. 1. Fig. 3 is a fragmentary perspective, looking at the back side of the 25 blade.

For the purpose of separating valuable fiber from the stalk or husk in which it grows, it is customary to break the stalk by 30 various operations and the fiber is then separated therefrom. My invention consists in a novel means of separating and grading the fiber. This means consists of a blade A, the ends of which are provided with means to 35 affix it in the machine in which it is to be used. The blade may stand in a vertical position and may have one end pivoted and the other end free to be raised or depressed by a handle or other suitable means. One side of 40 the blade is cut into parallel grooves as

shown at 2. The other side of the blade has its lower edge beveled as at 3, the bevel extending across the blade so that the edge intersects the grooves or channels upon the opposite side. This produces a saw-like edge 45 at the junction of the bevel and the grooved side, and this edge serves when the fiber-carrying material is drawn over a table beneath the edge to strip off and separate the shell or husk, leaving the fiber in a clean condition. 50 The fiber is also straightened out and is graded by the size of the grooves or channels; these being cut upon the side of the blade with reference to the fineness of the fiber which may be required. It will be 55 seen that as fast as wear takes place it is only necessary to grind the beveled portion until the intersecting grooves upon the opposite sides again form the series of small notches or teeth, which are required for the 60 proper operation of the device.

Having thus described my invention what I claim and desire to secure by Letters Patent is—

A decorticating blade comprising a thick 65 heavy blade, a series of shallow transverse parallel V-shaped ridges on one side thereof, a smooth diagonal side meeting said ridged side at an acute angle thereby forming an edge comprising pointed wedges adapted to 70 split and decorticate fibers which are drawn across the edge of the blade.

In testimony whereof I have hereunto set my hand in the presence of two subscribing witnesses.

HERBERT LEE HEATH.
